US00D817113S

(12) **United States Design Patent** (10) **Patent No.:** **US D817,113 S**
(45) **Date of Patent:** **** May 8, 2018**

(54) **LUNCH BOX**

(71) Applicant: **Abdoolally Ebrahim Housewares Limited**, Kowloon (HK)

(72) Inventor: **Wai Hang Wong**, Kowloon (HK)

(73) Assignee: **Abdoolally Ebrahim Housewares Limited**, Kowloon (HK)

(**) Term: **15 Years**

(21) Appl. No.: **29/557,495**

(22) Filed: **Mar. 9, 2016**

(51) LOC (11) Cl. **09-07**

(52) U.S. Cl. **D7/629**
USPC ....
